[57] CLAIM

The ornamental design for a tip for soap dispenser pump, as shown and described.

DESCRIPTION

FIG. 1 is a front-side perspective view of the tip for soap dispenser pump;

FIG. 2 is a rear-side perspective view thereof;

FIG. 3 is a rear elevation thereof;

FIG. 4 is a right side elevation thereof;

FIG. 5 is a top side elevation thereof;

FIG. 6 is a left side elevation thereof;

FIG. 7 is a front elevation thereof;

FIG. 8 is a bottom side elevation thereof, the broken line depiction of a pump hose being for illustrative purposes only and forming no part of the claimed design.
